FRUIT CUP OR THE LIKE

Willis R. Bengert, 2983 Crescent Road,
Pebble Beach, Calif. 93953

Filed May 15, 1972, Ser. No. 253,702

Term of patent 14 years

Int. Cl. D7—01

U.S. Cl. D7—13

FIG. 1.

FIG. 2.

FIG. 3.

FIG. 4.

FIG. 1 is a top perspective view of a fruit cup or the like showing my new design;

FIG. 2 is a partial elevational-sectional view thereof;

FIG. 3 is a top plan view thereof; and

FIG. 4 is a bottom plan view thereof.

I claim:

The ornamental design for a fruit cup or the like, substantially as shown.
